(57) CLAIM

The ornamental design for an escutcheon for shower arm, as shown and described.

DESCRIPTION

FIG. 1 is a perspective view of an escutcheon for shower arm showing my new design;

FIG. 2 is a side view thereof;

FIG. 3 is a front end view thereof; and,

FIG. 4 is a rear end view thereof.

The broken lines in the Figures are for illustrative purposes only and form no part of the claimed design.
